UNITED STATES PATENT OFFICE.

HENRY L. HEISLER, OF CHICAGO, ILLINOIS.

DESIGN FOR A VACUUM-JACKETED CARAFE.

58,091.

Specification for Design.

Patented June 7, 1921.

Application filed October 1, 1920. Serial No. 414,125. Term of patent 7 years.

To all whom it may concern:

Be it known that I, HENRY L. HEISLER, a citizen of the United States, residing at Chicago, in the county of Cook and State of Illinois, have invented a new, original, and ornamental Design for a Vacuum-Jacketed Carafe, of which the following is a specification, reference being had to the accompanying drawing, forming part thereof.

The figure is an elevation of a vacuum-jacketed carafe, showing my new design.

I claim:

The ornamental design for a vacuum-jacketed carafe, as shown.

HENRY L. HEISLER.
